UNITED STATES PATENT OFFICE.

SAMUEL RILEY LEWIS, OF EL PASO, TEXAS.

CROWN-SETTER.

1,345,608.

Specification of Letters Patent.

Patented July 6, 1920.

Application filed May 5, 1920. Serial No. 379,078.

To all whom it may concern:

Be it known that I, SAMUEL R. LEWIS, a citizen of the United States, residing at El Paso, in the county of El Paso and State of Texas, have invented a new and useful Crown-Setter, of which the following is a specification.

By way of explanation, it may be stated that, in order that a crown may fit properly on a tooth, it is necessary that the crown have impressions corresponding with the irregularities of the tooth, to the end that the teeth on the upper jaw and on the mandible may articulate properly, after the crown has been placed on the tooth.

It is the object of this invention to provide novel but simple means whereby the indentations of impressions may be made in the crown, the device being so constructed that impressions of different sizes may be made with the same instrument.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 discloses, in side elevation, a tool constructed in accordance with the invention; Fig. 2 is a plan of the tool; Fig. 3 is an end elevation of the tool.

The instrument forming the subject matter of this application is of the pliers type and comprises crossed handles 1 provided with transverse jaws 2 which are bifurcated as shown at 3 to form inwardly curved fingers 4, spaced widely apart and preferably of circular cross section. The fingers of one jaw are supplied with concaved terminal

recesses 5, the fingers of the other jaw having convexed tips 6 coöperating with the recesses 5. The recesses 5 are of different diameters, and the tips 6 are spaced accordingly. The handles 1 are connected at their point of crossing by a pivot element 7. A spring strip 8 is secured at one end, as indicated at 9, to one of the handles 1, near to the extremity thereof, the spring having a curved end 10 bearing slidably upon the other handle, adjacent to the pivot element 7. The spring 8, obviously constitutes a means for separating the working ends of the tool.

The crown may be placed on either of the fingers which have the recesses 5, and when the handles 1 are pressed together, the corresponding tip 6 will effect the necessary indentation of the crown. Since there are two recesses 5, of different diameters, and since the tips 6 are of different diameters, impressions of different shapes may be made, thereby widening the field of use of the instrument. Although the tool may be employed for making impressions of different diameters, the fingers 4 are separated far enough, transversely, so that when one set of the elements 6—5 is in use, the other set 75 of fingers 4 will not interfere with the operation of the tool.

Having thus described the invention, what is claimed is:—

A tool of the class described comprising crossed handles provided with jaws which are bifurcated to form inwardly extended fingers, the fingers of one jaw having concaved terminal recesses of different sizes and the fingers of the other jaw having convexed tips of different sizes corresponding to the recesses and coöperating therewith; and means for pivotally connecting the handles at their point of crossing.

In testimony that I claim the foregoing as my own, I have hereto affixed my signature in the presence of two witnesses.

SAMUEL RILEY LEWIS.
